AUTOMOBILE SPRING

Filed Sept. 27, 1921

2 Sheets-Sheet 2

UNITED STATES PATENT OFFICE.

GEORGE LOFFI, OF GARRETT, INDIANA.

AUTOMOBILE SPRING.

Application filed September 27, 1921. Serial No. 503,570.

To all whom it may concern:

Be it known that I, GEORGE LOFFI, a citizen of the United States, residing at Garrett, in the county of De Kalb and State of Indiana, have invented a new and useful Automobile Spring, of which the following is a specification.

The device forming the subject matter of this application is a vehicle spring, and the 10 invention aims to provide a spring which will possess unusual resiliency and be effective under a heavy load, or when the vehicle passes over an obstacle.

It is within the province of the disclosure 15 to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that, within the scope of what is claimed, changes in 25 precise embodiment of the invention shown can be made without departing from the spirit of the invention.

In the accompanying drawings:—

Figure 1 shows in side elevation, a device 30 constructed in accordance with the invention; Figure 2 is a detail enlarged from Figure 1, parts being broken away; Figure 3 is an elevation wherein the structure is viewed at right angles to the showing of Figure 2, parts appearing in elevation; Figure 4 is a section on the line 4—4 of Figure 3; Figure 5 is a section on a plane taken at right angles to the cutting plane of Figure 4.

In carrying out the invention, there is 40 provided a cruciform support 1 made up of plates 2 and 3 disposed at right angles to each other, the plates being halved together, at their point of crossing, as indicated at 4, the plate 2 being located above the 45 plate 3 at the point where the plates cross. A spacer 5 rests on the plate 2 and carries the intermediate portion of a main leaf spring 6. U-bolts or like clamping devices, denoted by the numeral 7, extend around the plate 3 and straddle the spring 6, in spaced relation, the U-bolts carrying yokes 8, resting on the spring 6 and held in place by nuts 9 threaded on the U-bolts.

Carrying plates 10 are disposed on opposite sides of the spacer 5 and rest on the plate 3. A bowed spring 14 extends trans-

versely of the main spring 6 the spring 14 having eyes 11, through which pass securing elements 12 engaged with the carrying plates 10. The spacer 5 is cut away as indicated at 60 30, and rests on the ends of the spring 14, adjacent to the eyes 11. A securing element 15 passes through the plates 2 and 3, at their point of crossing, and is threaded into the spacer 5, the spacer 5 thus being held on the plate 2, and serving, in its turn, to retain the carrying plates 10 and the spring 14 in place. The securing element 15 has a head 16 whereby it may be rotated, a nut 17 being threaded on the securing element, the 70 nut bearing against the plate 3, as shown in Figure 5. If desired, the securing element 15 may be threaded into the plates 2 and 3, at their place of crossing.

The numeral 18 denotes a base plate 75 disposed below the plate 2 and carrying studs 19 mounted to slide in the plate 2. Compression springs 20 surround the studs 19 and bear against the plates 2 and 18. Nuts 21 are threaded on the upper ends of the 80 studs 19 and cooperate with the plate 2, to limit the separation of the plates 2 and 18 under the action of the springs 20.

The numeral 22 denotes an axle. The plate 18 extends longitudinally of the axle 85 22 and is held thereon by U-bolts 23 and yokes 24, or in other suitable manner. The ends of the spring 6 are attached at 25, in the common way, to the chassis bar 26 of a vehicle frame.

In practical operation the spring 6 will 90 exercise its usual function. In case the vehicle is carrying an unusually heavy load, or when the vehicle passes over an obstacle, the chassis bar 26 will come into contact 95 with the bowed auxiliary spring 14 and the same will be compressed, the additional load, or the strain due to passing over an obstacle, being taken care of in this way. The springs 20 are adapted to yield and, 100 thus, additional resiliency will be provided.

What is claimed is:—

1. The combination with the frame and axle of a vehicle, of a bowed main spring assembled with the frame; a support; a spacer on the support and engaging the main spring; a bowed auxiliary spring disposed transversely of the main spring and extended between the main spring and the frame; means for securing the ends of the auxiliary spring to the spacer; means for securing the spacer to the support; means 105
- 110

for securing the main spring to the support; and means for attaching the support to the axle.

2. The combination with the frame and
5 axle of a vehicle, of a bowed main spring
assembled with the frame; a support; a
spacer on the support and engaging the
main spring; a bowed auxiliary spring dis-
10 posed transversely of the main spring and
extended between the main spring and the
frame; means for securing the spacer to the
support; means for securing the main
spring to the support; means for attaching
15 the support to the axle; and means for se-
curing the ends of the auxiliary spring to
the spacer, said means comprising plates
disposed on opposite sides of the spacer and
united by securing elements which are en-
20 gaged with the ends of the auxiliary spring,
the spacer being cut away so as to over-
hang and engage the ends of the auxiliary
spring.

3. The combination with the frame and

axle of a vehicle, of a bowed main spring
assembled with the frame; a support; a 25
bowed auxiliary spring disposed trans-
versely of the main spring and extended be-
tween the main spring and the frame in
spaced relation to the frame; means for
connecting the ends of the auxiliary frame 30
to the support; means for connecting the
support to the main spring; a plate dis-
posed below the support; means for connect-
ing the plate with the axle; means for con-
necting the plate with the support for rela- 35
tive vertical movement; and compression
springs carried by the last specified means
and interposed between the plate and the
support.

In testimony that I claim the foregoing 40
as my own, I have hereto affixed my sig-
nature in the presence of two witnesses.

GEORGE LOFFI.
